CLAIM

The ornamental design for a heart-shaped plastic paper clip, as shown and described.

DESCRIPTION

FIG. 1 is a front elevational view of a heart-shaped plastic paper clip showing my new design;

FIG. 2 is a top plan view;

FIG. 3 is a side elevational view, the opposite side being a mirror image thereof;

FIG. 4 is a bottom plan view; and

FIG. 5 is a cross-sectional view thereof, taken along line V—V of FIG. 1.

Fig. 2.
